UNITED STATES PATENT OFFICE.

ARTHUR L. STAPLES, OF NEW HAVEN, CONNECTICUT, ASSIGNOR TO WINCHESTER REPEATING ARMS COMPANY, OF NEW HAVEN, CONNECTICUT, A CORPORATION.

HANDLAMP SWITCH.

Application filed February 21, 1921. Serial No. 446,736.

To all whom it may concern:

Be it known that I, ARTHUR L. STAPLES, a citizen of the United States, residing at New Haven, in the county of New Haven, State 5 of Connecticut, have invented certain new and useful Improvements in Handlamp Switches; and I do hereby declare the following to be a full, clear, and exact description of the invention, such as will enable 10 others skilled in the art to which it appertains to make and use the same.

The present invention relates to portable electric lamps comprising a casing, a battery and an incandescent lamp mounted therein, 15 and a contact device on the casing by which the flow of current from the battery through the lamp may be controlled at will.

In a portable lamp of this character, it is desirable that the user shall be able to flash 20 the lamp, that is, light it for short periods of time, as in signaling, or for such length of time as it is convenient for the operator to hold his thumb on the contact device. It is also desirable that means be provided for 25 closing the switch to light the lamp for a longer period of time and without the need for continuous thumb pressure on the contact mechanism.

It is an object of the present invention to 30 provide a hand-lamp with a contact mechanism so arranged that the lamp can be flashed or can be permanently lighted, as desired, but with the additional feature that the contact mechanism cannot be locked in 35 closed-circuit position through accidental pressure on the contact device. This permits the hand-lamp to be carried about with tools or in the pocket of an automobile door without the danger that when the lamp is 40 needed its battery will be found exhausted because, through accident, the switch has been closed and the lamp has been lighted without the knowledge of the user.

Other objects and advantages will become 45 apparent from the following description, which is to be taken in conjunction with the accompanying drawings, wherein—

Fig. 1 is a view in side elevation of a hand-lamp embodying my invention and 50 having a portion of the casing broken away.

Fig. 2 is an end elevation thereof.

Fig. 3 is an enlarged broken internal view 55 of a portion of one of the end walls showing the inner side of the circuit closing device on the line 3—3 of Fig. 1.

Fig. 4 is an enlarged broken view in vertical section on the line 4—4 of Fig. 2, showing the circuit closing device in its open circuit position.

Fig. 5 is a similar view in closed circuit 60 position.

Fig. 6 is a similar view in transverse section on the line 6—6 of Fig. 2.

Fig. 7 is a view corresponding to Fig. 4 of an alternative form of my invention. 65

Fig. 8 is a view thereof corresponding to Fig. 3.

Fig. 9 is a view thereof corresponding to Fig. 6 on the line 9—9 of Fig. 7.

In carrying out my invention as herein shown I employ a sheet metal casing 10 of substantially parallelopipedal shape except that two opposed sides are approximately semi-cylindrical. In one of these sides, near the upper end thereof, I form a perforation 11 which is surrounded by a slightly raised rim 12 formed from the metal of the case and lying in a plane. In this perforation, and flush with the edge of it, is a flat push-button 13 formed about in the middle of a sheet metal spring-contact 14 which lies snugly against and conforms to the inner side of the case below the push-button and is rigidly attached to the case by a rivet 15.

Above the push-button, the spring-contact 14 is bent inwardly away from the case for a short distance as at 16 at an angle of about 45°, then upwardly again as at 17 and finally inwardly again at an angle of about 45° as at 18. The portion 17 of the spring-contact 85

has a transverse slot 19 for the reception of an inwardly turned lug 20 formed on a slide 21 which lies against the inner surface of the case and is held in place by a double pair of inturned lugs 22 formed on the edges 90 of the longitudinal walls of a hollow slideable sheet metal thumb-piece 23 located on the outer surface of the case 10 just above the rim 12. The said side walls of the thumb-piece extend through a pair of parallel vertical slots 24 in the case 10. In the open circuit or normal position of the parts, the slide 21 is held against movement by the engagement of the walls of the slot 19 with the lug 20.

In all other respects the casing is of ordinary construction. The bottom is hinged to admit a battery 25 contained in the usual insulating wrapper and having the customary sheet metal spring contacts 26 and 110

27 the latter being positioned alongside of but not in contact with the upper end 18 of the spring contact 14 when the latter is in its normal position.

5 The other contact 26 of the battery presses against the inner terminal of an electric bulb 28, of ordinary construction, which is mounted by means of its outer threaded terminal in the threaded lower end of a 10 funnel shaped bulb-housing 29 formed in the top surface of the case 10. Thus there is an electrically complete circuit from the spring-contact end 18 successively through the spring-contact 14, the rivet 15, the case 15 10, the bulb 28, the spring-contact 26, the battery 25 and the spring-contact 27. This circuit is closed except for the small gap between the battery spring-contact 27 and the spring-contact end 18. Pressure on the 20 push-button will force the spring-contact end 18 inward into engagement with the contact 27 closing the circuit and lighting the lamp, until the pressure is released and the spring-contact 14 returns to its normal 25 position breaking the circuit between the contacts 27 and 18.

When the push-button is pushed in, the lug 20 of the slide 21 is released from the slot 19 and is then free to move. If the 30 thumb-piece 23 be then pushed upwardly as in Fig. 5 the lug 20 will move out over the spring-contact 17 and prevent the same from springing back and breaking the circuit until the thumb-piece is pushed down again 35 to the position shown in Fig. 4 when the lug 20 snaps into the slot 19 and the circuit is broken.

In the alternative form shown in Figs. 7 40 and 9 the slide 30 is a vertically arranged roughly rectangular piece of sheet metal having at either end a transverse slot 31 to receive the wall of the casing 10 at the inner ends of a pair of slots 32 opening out of the perforation 11 on opposite sides thereof. The slide 30 rises through the slots 32 and also through a clearance slot 33 in the 45 spring-contact 14, the latter slot being of the same length as the slide 30 which is held therein against movement, until the 50 spring-contact is depressed sufficiently to clear the forward end thereof from the slide, which may then be slid forward over the spring contact to hold the same down in circuit-closing position. This motion of the 55 slide relative to the casing 10 is permitted by the fact that the distance between the bottom ends of the slots 31 is less than the distance between the bottom ends of the slots 32.

60 Various changes in the details of the constructions disclosed may be made without departing from the principles of this invention.

I claim:

65 1. In a hand lamp, a casing, a battery hav-

ing an exposed terminal and a bulb housed therein, and means for closing the circuit through said battery and bulb, including a 70 depressible contact strip having an offset portion adjacent its free end to engage said terminal, said strip being connected at the other end to the casing and formed to provide a manually engageable push button forwardly of said connection, and a locking member slidably mounted on the casing 75 forwardly of said push button, and means within the casing and connected to said locking member to be moved thereby to lock the contact strip in circuit closing position.

2. In a hand lamp, a casing, a battery and 80 bulb housed therein, and means for closing the circuit through said battery and bulb, including a depressible contact strip connected at its rear end to the casing and formed with an offset portion adjacent its 85 free end, and also formed to present a manually engageable portion accessible from the exterior of the casing to depress said strip to circuit closing position, said strip being provided with an opening in said offset portion, and a locking member slidably mounted on the casing and having a part normally received in said opening.

3. In a hand lamp, a casing, a battery and 90 bulb housed therein, and means for closing 95 the circuit through said battery and bulb, including a depressible contact strip connected at its rear end to the casing and formed with an offset portion adjacent its free end, and also formed to present a manually engageable portion accessible from the exterior of the casing to depress said strip to circuit closing position, said strip being 100 provided with an opening in said offset portion, and a locking member slidably mounted on the casing and having a part normally received in said opening, said locking member being 105 slidably forwardly to engage a solid portion of the strip after the latter has been depressed to lock it in circuit closing 110 position.

4. In a hand lamp, a casing having an opening, a battery and bulb housed therein, the battery having an exposed terminal adjacent its upper end, means to close the circuit through the battery and bulb, including a depressible contact strip lying adjacent the inner surface of the casing secured at one end thereto and formed with a projecting portion extending into the casing opening 115 for manual engagement, and with an inwardly offset portion adjacent its free end to engage the battery terminal, and means slidably mounted on the casing adapted to engage the offset portion of said strip to 120 lock it in circuit closing position.

5. In a hand lamp, a casing having an opening, a battery and bulb housed therein, the battery having an exposed terminal adjacent its upper end, means to close the cir- 125 130

cuit through the battery and bulb, including a depressible contact strip lying adjacent the inner surface of the casing secured at one end thereto and formed with a projecting portion extending into the casing opening for manual engagement, and with an inwardly offset portion adjacent its free end to engage the battery terminal, and means slidably mounted on the casing adapted to engage the offset portion of said strip to lock it in circuit closing position, said means being normally received in an opening in the strip.

6. In a hand lamp, a casing having an opening, a battery having an exposed terminal and a bulb housed therein, and means for closing the circuit through said battery and bulb, including a depressible contact strip having an inclined portion adjacent its free end to engage said terminal, said strip being connected at the other end to the casing and formed to provide a manually engageable push button forwardly of said connection, said button being disposed in the casing opening and standing normally flush with the surface of the casing, and a locking member slidably mounted within the casing and movable to a position above the contact

strip to lock the strip in circuit closing position, said member being normally received in an opening in the strip.

7. In a hand lamp, a casing having an opening, a battery having an exposed terminal at its upper end and a bulb housed therein, means for closing the circuit through said battery and bulb, including a depressible contact strip secured at its rear end to the casing, and having an inwardly inclined portion adjacent its forward end to be depressed into engagement with the exposed terminal, a locking member slidably mounted within the casing and movable only after the contact strip has been depressed to a position between the casing and strip to retain the latter in circuit closing position, said strip being formed with a push button standing in the casing opening normally flush with the surface of the casing.

In testimony whereof, I have signed this specification in the presence of two subscribing witnesses.

ARTHUR L. STAPLES.
